UNITED STATES PATENT OFFICE.

WALTER J. TURNBULL, OF NEW ORLEANS, LOUISIANA.

DESIGN FOR A CLEANER FOR KITCHEN UTENSILS.

SPECIFICATION forming part of Design No. 32,919, dated July 10, 1900.

Application filed June 14, 1900. Serial No. 20,372. Term of patent 7 years.

To all whom it may concern:

Be it known that I, WALTER J. TURNBULL, a citizen of the United States, and a resident of New Orleans, in the parish of Orleans and State of Louisiana, have invented and produced a new and original Design for a Cleaner for Kitchen Utensils, of which the following is a specification, reference being had to the accompanying drawings, forming a part thereof, in which—

Figure 1 is a perspective view of a cleaner for kitchen utensils embodying the features of my design, and Fig. 2 is a front elevation of the same.

The leading features of the design consist in two opposing members A and B, connected at one end by a bow member C, the member B having a transverse shoulder *b* extending in direction of the opposing member A, while the latter member terminates at its lower end in a serrated flange *a*, directed toward the member B.

The minor features of the design consist in the inwardly-curved side lines D of the two members and the increased length and transverse dimensions of the lower portion of the member B over corresponding portions of the member A, together with the marginal contours of the lower corners of the member B, one corner *d* being angular and the other 30 corner *d'* curved.

Having thus described my invention, I claim as new and desire to secure by Letters Patent—

The design for a cleaner for kitchen utensils, herein shown and described.

In testimony whereof I have signed my name to this specification in the presence of two subscribing witnesses.

WALTER J. TURNBULL.
